PUMP

Elek K. Benedek, Cleveland, Ohio, assignor to The
Cleveland Pneumatic Tool Company, Cleveland,
Ohio, a corporation of Ohio

Application December 12, 1940, Serial No. 369,852

7 Claims. (Cl. 103—161)

This invention relates broadly to rotary, multiple, radial piston pumps, but more particularly to improvements in such pumps wherein reciprocation of the pistons is effected through the rotation of inner and outer reactance polygonal rings.

One object of this invention is to produce such a pump with a one piece inner and a one piece outer reactance ring, thereby materially reducing the manufacturing cost while enabling the maintenance of closer tolerances and resulting in a construction particularly adapted for high production with maximum degree of accuracy.

Another object of this invention is to arrange and dispose such reactance rings in a manner eliminating their possible misalignment and providing for them adequate bearing means enabling their free rotation.

Another object of this invention is to provide such a pump with a novel output controlling mechanism depending for its operation upon pressure variation of the fluid supplied by the pump.

Another object of this invention is the production of a pump equipped with a simple and efficient valvular mechanism and a system of inlet and outlet ports so proportioned and arranged as to enable a free flow of fluid assuring complete filling and discharge of the pump cylinders irrespective of the length of stroke of the pump pistons.

Another object of this invention is to provide a flexible connection between the driving shaft and the driven parts of the pump, thereby preventing the driven parts from being subjected to undue stresses resulting from a misaligned drive shaft relative to such parts.

Other objects and advantages more or less ancillary to the foregoing reside in the specific construction and aggroupment of the elements peculiar to this structure, as will become apparent from a more complete examination of this specification.

In the drawings:

Fig. 1 is a longitudinal sectional view of a pump embodying the invention.

Fig. 2 is a cross sectional view taken in a plane indicated by line 2—2 in Fig. 1.

Fig. 3 is a cross sectional view taken in a plane indicated by line 3—3 in Fig. 1 and illustrating the power unit in one operative position.

Fig. 4 is a view similar to Fig. 3 but illustrating the power unit in inoperative or neutral position.

Fig. 5 is a cross sectional view taken in a plane indicated by line 5—5 in Fig. 1 illustrating the

bearing in a position corresponding to that of the power unit in Fig. 3.

Fig. 6 is a view similar to Fig. 5, but illustrating the bearing in a position corresponding to that of the power unit in Fig. 4.

Referring to the drawings, 10 illustrates a substantially cylindrical housing provided at one end with an integral suspension flange 11 apertured as at 12 to accommodate stay bolts through which the housing may be secured to any suitable driving motor (not shown). The apertured portion of the flange 11 is spaced from the housing to accommodate the usual nuts cooperating with the stay bolts for securing the housing in position. 15 The other end of the housing 10 is closed by an end plate or cover 13 secured in position by cap screws 14, which cover is provided with an enlarged center bore 15 having pressed therein a cylindrical pindle 16 which extends therefrom internally into the housing 10 and is maintained against movement relative thereto by any suitable means such as a weld 17 between the pindle and the cover 13.

20 Rotatably mounted on the pindle 16 and consequently in the housing 10, there is a rotor 18 having two hubs 18' and 18'' extending therefrom in opposite directions and closely fitted for rotation on the pindle 16. The hub 18' has its outer end reduced to form a shafted portion 19 journaled within an antifriction bearing 20 mounted in the flange 11 against axial movement relative thereto. To prevent axial movement of the rotor 18, the bearing 20 has one of its sides resting against an annular shoulder 21 ending the shafted portion 19, while the other side engages a spring clip 22 integrally mounted on the shafted portion 19. An end plate 23, mounted within a counterbore 24 of the flange 11, holds the bearing 20 in position and carries a wiper 25 active on the outer end portion of the rotor shaft 19 located within the plate 23.

25 The reduced portion 19 of the rotor 18 is provided with a flat bottom bore 26 accommodating the cylindrical head 27 of a driving shaft 28, the head being slightly smaller than the bore to permit slight lateral movement of the shaft relative to the rotor. As shown, the shaft 28 protrudes from the housing where it is provided with driving teeth 29 through which the shaft 28 may be operatively connected with any suitable driving motor (not shown). The shaft 28 is also provided with a bore 30 forming, close to the inner end thereof, an internal annular shoulder 31 on which rests the lip of a cup-shaped spring 32 through which the shaft 28 is connected to

the rotor 18 by a cap screw 33. Due to the resiliency of the spring 32, driving shaft 28 will be free to move laterally relative to the rotor 18 to enable slight misalignment of the shaft relative to the motor without transmitting undue lateral thrusts to the rotor 18. The driving connection between the rotor 18 and the shaft 28 is shown to include two relatively small pins 34 partly carried by the rotor and partly by the shaft and calculating to transmit rotation to the rotor under a normal condition, but capable of being sheared off when the rotor is subjected to an accidental load which would otherwise submit the motor connected to the driving shaft to a damaging load.

Intermediate its ends, the rotor 18 is provided with a double row of seven equally spaced radially extending cylinders 35, each having a cylindrical bore 36 extending axially therethrough. As shown, the inner end of each cylinder bore 36 is somewhat reduced to form a fluid passage 37, the purpose of which will be explained later. Each cylinder 35 of one row is parallel to and longitudinally spaced from the juxtaposed corresponding cylinder of the other row to form a set of two cylinders united by a longitudinally extending reinforcing fin 38.

Reciprocably mounted within each cylinder bore 36, there is a piston 39 formed with a T-shaped head 40. Surrounding the two rows of pistons 39, there are two reactance rings 41 and 42, the former or inner ring 41 being coaxially mounted within the latter or outer ring 42. The inner ring 41 has its peripheral wall machined to form a perfect seven sided polygon, while the outer ring 42 is internally shaped to correspond to the peripheral shape of the inner ring. The interior of the outer ring is larger than the exterior of the inner ring to provide each side of the polygon with two perfectly parallel walls forming thrust faces 44 and 45 each perfectly normal to the longitudinal center axis of its adjacent cylinder bore 36 formed within the rotor 18. The thrust faces 44 and 45 of each side of the polygon are spaced from each other to form a slot or opening 43 of a width capable of accommodating the T-shaped heads 40 of the pistons 39, which heads are closely fitted between the thrust faces 44-45 for slidable movement therebetween. Each thrust face 44 is provided with an elongated opening 46 through which the piston 39 passes.

The two reactance rings 41 and 42 are mounted between and carried by two supporting rings 47 and 48, which have their inner side walls each formed with a perfectly circular shallow groove 49 within which the reactance rings are closely fitted, thereby assuring perfect coaxial alignment of the rings. A plurality of cap screws 51 rigidly secure the outer reactance ring 42 to the supporting rings 47 and 48, while the inner reactance ring 41 is similarly secured to the supporting rings by cap screws 52. The supporting rings 47 and 48 are each provided with a hub 53 journaled within a bearing 54, which bearing has its inner side wall resting against an annular step 55 formed on the hub and its outer side wall engaging a spring clip 56 integrally carried by the hub, thereby preventing axial movement between the supporting rings and bearings. The hubs 53 have an enlarged bore 57 extending axially therethrough to permit radial movement of the supporting rings 47 and 48 relative to the hub portions 18' and 18'' of the rotor 18.

Surrounding and fitted on each bearing 54,

there is a band 58 provided with two diametrically opposed blocks 59 having end walls forming two parallel sliding surfaces 50 mounted between and for slidable engagement with two corresponding pads 60 protruding internally from the wall of the housing 10. Disposed at right angles from the blocks 59, each band 58 has its lower portion provided with a spring pilot 61 around which is seated one end of a compression spring 62 having its other end resting on the bottom of a cup-shaped plug 63 screwed in the housing 10. The tension of the compression spring 62 is adjustable by removing or adding shims 64 between the head of the plug and the housing 10. Diametrically opposed to each compression spring 62, the housing 10 is also provided with a radially extending threaded bore 65 having mounted therein a small casing 66. This casing extends partway into the housing 10 and is provided with a cylindrical bore 67 opening through its inner end and having slidably mounted therein a pressure fluid piston or plunger 68 adapted to bear on the band 58 surrounding the bearing 54. Each casing 66 has its upper end also threaded to receive a pipe connection or nipple 69 through which a pipe or conduit 70 is screwed to each casing 66 for admitting pressure fluid to the inner end of the plunger 68 through a port 71.

The end plate of cover 13 has its outer end wall provided with two diametrically opposed threaded bores 72 each adapted to receive a pipe bushing 73 through which conduits 74 and 75 are connected to the cover 13. The conduit 74 opens into a chamber 76 provided in the cover 13 while the conduit 75 opens into a similar chamber 77 also provided in the cover. As shown in Fig. 2, the chamber 76 is in constant communication with the pintle 16 through a gap or opening 78 while the chamber 77 is similarly in constant communication with the pintle 16 through a gap 79 diametrically opposed to the gap 78. The chambers 76 and 77 are located within a vertical plane wherein the pintle 16 is provided with two diametrically opposed slots 80 and 81 forming between them a bridge 82, the slot 80 opening in the chamber 76 through the gap 78 while the slot 81 opens in the chamber 77 through the gap 79. Within the vertical planes passing through the two rows of pistons 39, the pintle 16 is provided with diametrically opposed slots 83 and 84 corresponding to the slots 80 and 81 respectively and also forming between them a bridge 85. Fig. 3 which is taken through the vertical plane indicated by line 3-3 in Fig. 1 clearly shows the slots 83 and 84 and bridge 85 and it is to be understood that the rotor and pintle construction within the vertical plane passing through the other row of pistons shown in Fig. 1, is identical to that shown in Fig. 3. The pintle slot 80 is in constant communication with its slots 83 through two passages 86 extending longitudinally in the pintle 16, while the slot 81 is similarly connected to the slots 84 through two longitudinal passages 87. In practice, the passages 86 and 87 are drilled from the outer end of the pintle 16 and subsequently closed at that end by any suitable means such as plugs 88.

Tapped into the conduit 74 by a suitable connection 89, there is a by-pass pipe 90 connected to the two pipes 70 by a T connection 91.

In practice, the pump is fastened to a driving unit, such as a motor of any suitable type, by bolts (not shown) extending through the holes 12 of the suspension flange 11, while the shaft 28 is connected to the motor shaft through the driv-

ing teeth 29. From the shaft 28 rotation is transmitted to the rotor 18 through the driving pins 34. Due to the flexible connection between the shaft 28 and the rotor 18 which includes the cup-shaped resilient member 32, limited misalignment of the shaft 28 relative to the center axis of the rotor 18 is permitted without transmitting undue lateral thrust to the rotor or other parts of the pump.

Normally, the bearings 54, or more particularly the whole eccentric unit which includes the reactance rings 41-42, the supporting rings 47-48, the bearings 54 and bands 58, being acted upon by the compression springs 62 will maintain the plungers 68 at the inner end of their strokes within the casings 66, in which instance the outer end of each plunger protrudes slightly from its casing for engagement with its bearing 54 or more particularly with the band 58 fitted over the bearing. In this position of the plungers 68, the entire eccentric unit is located in extreme eccentric position relative to the rotary axis of the rotor 18. Assuming now that the rotor 18 through the shaft 28 and driving pins 34 is rotated in a clockwise direction in Figs. 3 and 5, which rotation is of course transmitted to the pistons 39 carried by the rotor and from the pistons to the reactance rings 41 and 42 through the close fit of the piston heads 40 between the two thrust faces 44 and 45. The heads of the pistons 39 being thus mounted for rotation within a path eccentric relative to the center axis of the rotor 18, will upon rotation of the rotor 18 have axial reciprocation imparted thereto relative to the cylindrical bores 36 of the rotor 18, while the heads 40 of the pistons 39, due to the eccentricity between the axes of rotation of the rotor 18 and the reactance rings 41 and 42, will actually slide back and forth between the thrust faces 44 and 45, the elongated opening 46 through the thrust faces 44 enabling this back and forth slideable or tangential movement between the inner reactance ring 41 and the pistons 39. The degree of reciprocation of the pistons 39 or the length of their strokes within the cylinder bores 36 is of course governed by the extent of separation or eccentricity between the rotary axes of the rotor 18 and that of the reactance rings. In the present construction, the pintle's bridges 82 and 85 are parallel to the surfaces 50 of the blocks 59 slidably engaging the pads 60 which form guiding means for the reactance rings relative to the pintle 16. In other words, the longitudinal axes of the bridges 82 and 85 coincide with the sliding axis of the reactance rings 41 and 42, and since in Fig. 3 the axis of rotation of the reactance rings is located above the axis of rotation of the rotor 18, it will be understood that when each piston 39 is in the twelve o'clock position, it is at the end of its outer or suction stroke and in the six o'clock position it is at the end of its inner or compression stroke.

During rotation of the rotor 18 and consequently of the pistons 39 in a clockwise direction in Fig. 3, the pistons rotating from the six to the twelve o'clock position will gradually be moved out of their respective cylinder bores 36. In practice, the inlet conduit 75 has fluid supplied thereto from any suitable source. Due to the outward movement of the pistons 39, fluid from the conduit 75 will be drawn into the chamber 77 and therefrom into the slots 84 via the gap 79, slot 81 and passages 87. From the slots 84, the fluid will be drawn into the cylinder bores 36 in connection with the slots 84 through the passages 75

37, thereby gradually filling the inner portion of the bores preparatory to the expulsion of the fluid therefrom. As each piston bore reaches the twelve o'clock position, its corresponding passage 6 37 will be closed by the bridge 85, the width of which is somewhat greater than the diameter of the passage 37, thereby preventing escape of the fluid from the cylinder bores into the slots 84 when the pistons reach the end of their suction strokes. As the pistons are rotating from the twelve to the six o'clock position, they will gradually be pushed inwardly, thereby causing the fluid previously sucked or drawn into the cylinder bores 36 to be expelled therefrom by the pistons into the pintle's slots 83 through the passages 37, and from the slots 83 into the outlet conduit 74 via the passages 86, slot 80, gap 78 and chamber 76. As each piston reaches the six o'clock position, the passage 37 of its respective cylinder bore 36 will be closed by the bridge 85 to prevent possible communication of the slots 83 and 84 over the bridge 85.

From the foregoing description, it will be understood that the suction strokes of the pistons 25 39 are accomplished through the action of the inner reactance ring 41, or more particularly the action of its thrust faces 44 on the crossheads 40 of the pistons. The inner ring thus is subjected to forces applied in a radially inward direction at regularly spaced points. This load tends to compress or contract the ring. The compression strokes of the pistons are effected by the outer ring 42, or more particularly by the action of its thrust faces 45 against the crossheads 40 30 of the pistons. This outer reactance ring therefore is subjected to forces applied at regularly spaced points tending to expand the ring. In either of the rings the load applied to any one of its polygonal faces, whether compression in 35 the case of the inner ring or tension in the case of the outer one, is transmitted to the adjacent parts of the ring. In other words the load, before it is transmitted to the supports for the reactance rings, is absorbed by compression or tension stresses applied lengthwise of the ring. It will be noted also that two reactance rings may 40 be used to operate a plurality of sets of pistons, as herein illustrated, with no increase in the number of manufacturing operations so far as 45 the reactance rings are concerned.

In practice, the outlet conduit 74 is generally connected to a reservoir or tank from which pressure fluid may be drawn for operating any fluid actuated mechanism such as a landing gear retracting mechanism, hydraulic engine or the like. From the outlet conduit 74, the fluid is also supplied to the plungers 68 within the casings 66 through the by-pass conduit 90, the T connection 91, pipes 10 and ports 11, thereby subjecting the plungers to the action of the fluid pressure which gradually increases as the delivery of the fluid to the tank progresses. As the fluid pressure within the tank supplied by the outlet conduit 74 reaches the desired maximum, that fluid pressure active on the plungers 68 will gradually shift the bearings 54, the supporting rings 47 and 48 and consequently the reactance rings 41 and 42 into concentric position with the rotor 18. In other words, the fluid pressure active on the plungers 68 will overcome the effort of the compression springs 62 for shifting the reactance rings 41 and 42 into concentric position with the rotor 18. During this shift of the reactance rings, since their common axis of rotation is gradually moved closer to the axis of rotation of the rotor

18, the length of the strokes of the pistons 39 will also gradually be reduced, thereby gradually reducing the output of the pump. When the axis of rotation of the reactance rings and rotor finally coincide, the pistons 39 will rotate with the rotor 18 around the pintle 16 without having reciprocation imparted thereto, thereby preventing further supply of fluid to the tank even though the pump or more particularly its rotor 18 is still rotated through the drive shaft 28.

As the fluid pressure within the tank supplied by the outlet conduit 74 decreases, the fluid pressure active on the plungers 68 will decrease equally, thereby enabling the compression springs 62 to again shift the reactance rings 41 and 42 into more or less extreme eccentric position relative to the axis of rotation of the rotor 18, and consequently again imparting reciprocatory motion to the pistons 39 for supplying pressure fluid to the tank via the conduit 74 until that pressure again reaches a predetermined maximum. This maximum pressure of the fluid may be varied at will by adjusting the degree of compression of the springs 62, which is here rendered possible through the insertion or removal of shims 64 between the head of the plugs 63 and the housing 10.

Lubrication of the moving parts of the pump is effected by partly filling the housing 10 with liquid lubricant such as oil. Upon rotation of parts such as the supporting rings 41 and 48 and the reactance rings 41 and 42, lubricant stored within the housing 10 will be dashed to the several bearings and moving parts of the pump to afford positive and efficient lubrication thereof.

Although the foregoing description is necessarily of a detailed character, in order to completely set forth the invention, it is to be understood that the specific terminology is not intended to be restrictive or confining and it is to be further understood that various rearrangements of parts and modifications of structural detail may be resorted to without departing from the scope or spirit of the invention as herein claimed.

I claim:

1. In a rotary piston pump, a rotor having a plurality of radially arranged cylinders open at their outer ends, pistons in said cylinders, an eccentric unit comprising supporting means revoluble about an axis parallel with but eccentric to the axis of said rotor, a one-piece outer reactance ring and a one-piece inner reactance ring both carried by said supporting means, said rings having facing polygonal surfaces equal in number to said cylinders, and said pistons having crossheads bearing against said polygonal surfaces.

2. In a rotary piston pump, a rotor having a plurality of radially arranged cylinders open at their outer ends, pistons in said cylinders, an eccentric unit comprising supporting means revoluble about an axis parallel with but eccentric to the axis of said rotor, said supporting means comprising a pair of supporting rings, a one-piece outer reactance ring and a one-piece inner reactance ring disposed between said supporting rings and forming exclusive means for rigidly connecting said supporting rings, said reactance rings having facing polygonal surfaces equal in number to said cylinders, and said pistons having crossheads bearing against said polygonal surfaces.

3. In a rotary piston pump, a rotor having a plurality of radially arranged cylinders open at their outer ends, pistons in said cylinders, an

eccentric unit comprising supporting means revoluble about an axis parallel with but eccentric to the axis of said rotor, said supporting means comprising a pair of supporting rings having opposed annular grooves therein, a one-piece outer reactance ring having a cylindrical outer surface and a one-piece inner reactance ring having a cylindrical inner surface, said reactance rings being disposed between said supporting rings with their cylindrical surfaces bearing against the radially outer and inner walls of said grooves, and means for securing the reactance rings to the supporting rings to constitute a rigid connection between the supporting rings, said reactance rings having facing polygonal surfaces equal in number to said cylinders, and said pistons having crossheads bearing against said polygonal surfaces.

4. In a rotary piston pump, a rotor having a plurality of radially arranged cylinders open at their outer ends, pistons in said cylinders, an eccentric unit revolvable about an axis parallel to the axis of said rotor, reactance means carried by said unit for reciprocating the pistons, two bearings for said eccentric unit spaced lengthwise of the pump axis, said bearings being independently movable toward or away from the axis of said rotor, and adjusting means for exerting equalized fluid pressure upon said bearings for moving them in a given direction.

5. In a rotary piston pump, a housing, a rotor mounted therein having a plurality of radially arranged cylinders open at their outer ends, pistons in said cylinders, an eccentric unit revolvable about an axis parallel to the axis of said rotor, reactance means carried by said unit for reciprocating the pistons, two ball bearings for said eccentric unit spaced lengthwise of the pump axis, a steel band surrounding and gripping the outer race of each of said bearings, and coacting guide means on said housing and on each of said steel bands for controlling the direction of movement of said bearings during the adjustment of the eccentricity of the unit.

6. A rotary piston pump comprising a housing, a rotor in said housing having a plurality of radially arranged open ended cylinders, reciprocable pistons in said cylinders, an elongated eccentric unit surrounding said rotor for rotation therewith and connected to said pistons for imparting reciprocation thereto upon its rotation on an axis parallelly spaced from the rotary axis of said rotor, bearing means for the longitudinal ends of said unit, guiding means for said bearing means enabling movement of said unit in a variable distance of its rotary axis from that of said rotor, resilient supporting means for said bearing means, and distance controlling means between the rotary axes of said rotor and unit including a pair of fluid actuated elements concurrently active on said bearing means for maintaining said axes in parallel relation.

7. In an apparatus of the class described, the combination of a housing having a rotor extending longitudinally therein and a fluid tight seal carried by the housing in operative engagement with one end portion of the rotor, a blind bore within said one end portion of the rotor, a rotor driving member in said bore, resilient fastening means between said rotor and member enabling limited rocking movement of the latter relative to the former, and a rotation transmitting connection between said rotor and member.

ELEK K. BENEDEK.
